DEVICE FOR ATTACHING TWO SEPARABLE PARTS TOGETHER

Willard G. Axtell, Denver, Colo., assignor to Shwayder Bros., Inc., Denver, Colo., a corporation of Colorado

Application February 7, 1955, Serial No. 486,327

16 Claims. (Cl. 292—248)

This invention relates to devices for attaching two separable parts together along a joint therebetween, such as a draw bolt for attaching two sections of a luggage case or the like together.

Various types of devices for attaching two separable parts together have been utilized, particularly sections of luggage cases, including latches and locks of various types and draw bolts which have been utilized to pull or draw the sections together, as well as hold them together in closed position. One type of draw bolt which has been utilized extensively, since many thousands and perhaps millions of the same have been utilized on luggage cases, comprises a cap which is pivotally attached at its rear end to a link, in turn pivotally attached at its front end to a base which is mounted on one of the luggage case sections. The free end of the cap is provided with a plate having a hole therein for engaging a draw bolt pin attached to the other case section. A spring at each of the pivotal connections, between the link and the base and between the link and the cap, hold the cap normally in an upper or open position. For closing the case, the rear end of the cap is lifted or the front end pushed down until the front end engages the draw bolt pin, whereupon the rear end of the cap is pressed downwardly against the base. For opening the case, the rear end of the cap is pulled upwardly, which moves the cap forwardly, whereupon the front end of the cap may be lifted off the draw bolt pin. While such draw bolts provide a secure attachment of the parts, both the opening and closing manipulations thereof involve two sequential operations. Also, when the case is particularly full of garments or the like, the pressure of the garments or other articles disposed within the case may tend to force the case slightly open when the cap is first lifted, thereby requiring pressure against the case sections to hold them closed until the cap can be disengaged from the draw bolt pin. Thus, although highly satisfactory from the standpoint of service, stability and closure action, such a draw bolt sometimes involves difficulties in manipulation.

Other types of draw bolts or closure devices for luggage cases are too often unreliable in use, involving only a single part which is pushed into or out of closure position, such as a hasp hinge mounted on one section and when closed extending around a block on the opposite section. Unless a complicated construction, which involves additional manipulation, is utilized in connection with a hasp, it tends to fly open under relatively heavy stress and also tends to open at inopportune times, after a slight amount of wear has occurred. Other types of devices involve the same and additional difficulties and disadvantages.

Among the objects of the present invention are to provide a novel device for attaching two separable parts together along a joint therebetween; to provide such a device which is particularly adapted to be utilized as a draw bolt for attaching two sections of a luggage case or the like together; to provide such a device which involves a minimum of manipulation for opening and clos-

ing; to provide such a device which holds the parts securely together in closed position and does not tend to fly open under heavy stress; to provide such a device which does not tend to open under stress, after a slight amount of wear has taken place; to provide such a device which tends to remain in open position after opening; to provide such a device which will open readily, even when a luggage case or the like is particularly full of garments or other articles tending to cause the case to fly open when the device is opened; to provide such a device which may be manufactured relatively economically and installed readily; to provide such a device which will withstand the rigors of hard usage; and to provide such a device which is highly satisfactory in operation and use.

The foregoing and additional objects of this invention, together with the novel features and advantages thereof, will become apparent from the description which follows, taken in connection with the accompanying drawings, in which:

Fig. 1 is a fragmentary, perspective view of a portion of a luggage case on which is installed a draw bolt constructed in accordance with this invention;

Fig. 2 is a longitudinal section of the draw bolt of Fig. 1 in closed position and showing also certain portions of the luggage case to which the parts of the draw bolt may be attached;

Fig. 3 is a similar longitudinal section, but with the draw bolt in open position and the trigger depressed, as on opening;

Fig. 4 is a cross section taken along line 4—4 of Fig. 2;

Fig. 5 is a cross section taken along line 5—5 of Fig. 2;

Fig. 6 is a horizontal section, looking downwardly along line 6—6 of Fig. 2;

Fig. 7 is a perspective view of a base which forms a part of the draw bolt of Fig. 1;

Fig. 8 is a fragmentary horizontal section, looking upwardly along line 8—8 of Fig. 4;

Fig. 9 is a perspective view of a trigger, which forms a part of the draw bolt of Fig. 1; and

Fig. 10 is a fragmentary longitudinal section, similar to a portion of Fig. 3.

A device for attaching two separable parts together along a joint therebetween and constructed in accordance with this invention, such as a draw bolt, as in Fig. 1, may be installed on a luggage case having two sections 10 and 11 which are separable along a joint 12 therebetween, the joint 12 being at the meeting edges of the opposed sections 10 and 11. Normally, the luggage case sections 10 and 11 will be attached together by one or more hinges with a draw bolt placed along joint 12 at two or more positions, such as along the side opposite the hinges, or perhaps on the ends or other sides of the case. The draw bolt of Fig. 1, as shown also in Figs. 2 and 3, may include a cap C which is pivotally attached, as by a lost-motion connection, to a base B which may be mounted on section 10 of the luggage case. A trigger T may be mounted in the cap C for relative movement thereto and is adapted to engage a catch H, which is mounted on the other separable part, such as the luggage case section 11. The cap C also preferably engages the catch H, while a resilient block R may be mounted on the base B and the cap C may be provided with means for engaging and compressing the block R as the cap C and the trigger T engage the catch H. In general, when in closed position, as in Fig. 2, the force holding the luggage sections 10 and 11 together is transmitted through the cap C between the block R and the catch H, while the engagement of the trigger T with the catch H merely prevents the cap C from disengagement until the trigger T is actuated, as by being pushed inwardly to the position of Fig. 3 or Fig. 10. Thus, when the trigger T is disengaged from the

catch H, the cap C pivots upwardly about the base B, as to the position of Fig. 3 or Fig. 10, in which both the trigger T and the cap C clear the catch H, so that the joint 12 may open or be opened to separate the sections 10 and 11. It will be understood, of course, that when a plurality of draw bolts is utilized, each of the draw bolts is opened to the position of Fig. 3 or Fig. 10, before the luggage case itself is opened. In addition to the hinges mentioned previously, not shown because conventional, the luggage case may also be provided with a handle, a lock and other so-called hardware, all of which are conventional and therefore not shown.

Sections 10 and 11 of the luggage case of Fig. 1 may be provided around the peripheries thereof with interfitting strip means, such as in the manner disclosed and claimed in the copending application of Emmett H. Heitler, Serial No. 484,335, filed January 27, 1955, and as also shown in my copending application Serial No. 499,069, filed April 4, 1955, although the draw bolt of this invention may be applied to other and different types of luggage cases and may be used as a device for attaching together two separable parts other than sections of a luggage case, as will be readily understood. Thus, it will be understood that the construction of a luggage case as described herein is illustrative only and not in limitation of the construction or use of the device of this invention. As disclosed in the aforesaid copending applications, the luggage case section 10 may be provided with a tongue strip 13 and the section 11 with a groove strip 14, the strip 13 being provided with a tongue and the strip 14 with a groove, as shown, adapted to interfit with the sections in closed position, as in Fig. 2. Each of the strips 13 and 14 may be provided with a web 15, an outer flange 16 and an inner flange 17 with a wall 18 of the case extending between web 15 and outer flange 16 of each of the strips 13 and 14, the wall 18 being attached to the web 15 in any suitable manner, as by a series of spaced rivets or by the same rivets or other elements by which the draw bolts and other hardware parts are attached to the case, the latter preferably being attached to the web 15 of the respective strips. The wall 18 may comprise a strip of metal, such as magnesium alloy, which is provided on the outside with a bonded layer of wear-resistant material, such as a suitable plastic, although the wall 18 may be formed of fibreboard impregnated on one side or both sides with a suitable resin and provided on the outside with a bonded, wear resistant layer of a suitable plastic, or the wall 18 may be formed of any other suitable material. When the luggage sections 10 and 11 are provided with a lining, the lining conveniently extends into the space between inner flange 17 and web 15 of the strips 13 and 14, as in the manner disclosed and claimed in the aforesaid copending application of Emmett H. Heitler, Serial No. 484,335.

The base B may be attached to the case section 10 adjacent the joint 12, as by a rivet 19, which extends through the wall 18 to attach the base B to the web 15 of the strip 13, with the front edge of the base B conveniently abutting against the edge of outer flange 16 of the strip 13, as in Fig. 3. Similarly, the catch H may be mounted on the case section 11, also adjacent joint 12 and in opposed position to the base B, as by a rivet 20, which extends through the wall 18 to attach the catch H to web 15 of strip 14, the lower front edge of catch H similarly conveniently abutting against the edge of the outer flange 16 of strip 14.

The cap C, in Figs. 2-5, may comprise a top 25 from each lateral edge of which integral side flanges 26 and 27 extend downwardly, the lower edges of flanges 26 and 27 preferably being spaced slightly from the case walls 18 in closed position, as in Fig. 2, while the lower edge of each side flange 26 and 27 may be provided with a rectangular groove 28 disposed centrally thereof and shown more clearly in Fig. 3, to accommodate the ledges formed by strips 13 and 14 with the cap in closed po-

sition. It will be understood that groove 28 may be unnecessary in many instances, such as when the device of this invention is installed on a luggage case or other article which is completely flush across the joint between the two separable parts. The front end of the cap C, between side flanges 26 and 27, is preferably open to permit access to trigger T for movement thereof, while the rear end of the cap C may be closed by an end flange 29, with a bevel 30 provided at the lower end of flange 29 and also extending diagonally across the lower rear corners of side flanges 26 and 27, to permit the cap C to pivot upwardly, as to the position of Fig. 3 or Fig. 10, without interference occasioned by the lower rear edge thereof striking the wall 18. In addition, the bevel 30 may provide a stop for upward movement of the cap C, so as to maintain the cap in a convenient position for downward movement when the luggage case is to be closed. The cap C may also be provided with a pivot pin 31 which is mounted between the side flanges 26 and 27 adjacent the rear of the cap, as well as a front or roll pin 32 which extends between flanges 26 and 27 adjacent the front of the cap and on which a roll 33 is mounted, for engagement with the catch H when the draw bolt is closed. Also, a central pin 34 extends between the flanges 26 and 27, for a purpose described later, the rear pin 31, front pin 32 and central pin 34 conveniently being fixed pins. On its underside, the top 25 of the cap may be provided with a trough formed by longitudinally extending, depending flanges 35, as in Figs. 4 and 8, for reception of a spring 36, which normally pushes the trigger T resiliently into engagement with the catch H to hold the draw bolt in closed position. The flanges 35 are conveniently formed integrally, as by casting, with an abutment 37 and a pair of blocks 38, the latter being shown in Fig. 8 as cylindrical but the configuration of which may be varied considerably. Abutment 37 and pin 34 are engaged by one end of coil spring 36, while the outer edges of blocks 38 form a guide for the trigger T, in a manner hereinafter described.

Cap C may be formed of suitable material, such as an aluminum alloy which may be cast and then electro-lytically polished and plated to provide a suitable color, or an enamel, lacquer or synthetic resin finish may be utilized. Also, the pins 31, 32 and 34 may be hollow, as shown, conveniently formed from narrow strips of flat stock rolled around to an annular shape, so as to provide enough resiliency for a wedging action when driven into holes in flanges 26 and 27 drilled for that purpose. Of course, these pins may be solid and riveted over at the outer ends, or may be attached to the flanges 26 and 27 in any other suitable manner.

Base B has a bottom 40 which rests on the case wall 18, as indicated previously, with the front edge of bottom 40 abutting the flange 16 of strip 13, although in the event that a device of this invention is installed on a part which has a flush surface at the joint, more than one rivet 19 may be utilized, or base B attached in any other suitable manner. A side flange 41 upstands from each side of base 40, while an end flange 42 extends between the side flanges 41 at the front. Also, each of the side flanges 41 may be provided with a horizontally elongated slot 43 having a thickness slightly greater than the outer diameter of the rear pin 31 of the cap C, so that pin 31 may move along the slots 43 but also permit the cap C to pivot. The base B may be cast from a suitable material, such as aluminum alloy, and the surface thereof may be treated similarly to cap C.

The resilient block R is formed of rubber, either natural or synthetic, such as neoprene, and conveniently fits loosely between the side flanges 41 to permit compression, but abuts against the front flange 42 of base B. The block R may be cemented or otherwise suitably attached in position, or may be merely placed in position. In the latter case, to minimize the possibility of accidental misplacement, a lower leg 45 may extend rearwardly be-

neath cap pin 31. As will be evident from Fig. 2, when the cap C and trigger T are moved into engagement with catch H, the cap C is moved slightly forward, so that the pin 31 will engage and compress the block R. The distance which the pin 31 moves, between the positions of Fig. 2 and Fig. 3 need not be as great as indicated by Figs. 2 and 3, the same being slightly exaggerated for illustrative purposes. In addition, the top 46 of block R may be bevelled upwardly from rear to front so that when the cap C moves to the closed position of Fig. 2, the under side of the top 25 of the cap will engage the top of the block R to compress the block, so that the block will move the cap C upwardly, as to the position of Fig. 3, when the trigger T is released for opening the case. Of course, the top of the block R may have any other desired configuration. Each block R may be formed individually, as by molding, but more conveniently by cutting off individual blocks from an extruded strip having a cross section such as that shown in Fig. 3.

As shown in Fig. 9, the trigger T may be provided with parallel sides 50 and 51 connected by a front 52, the latter of which may be concave on the outside to facilitate the user exerting pressure against the front 52, as by one finger, in releasing the trigger T when the case is to be opened, as well as to minimize the possibility of the draw bolt being opened accidentally. Adjacent the front and at a position corresponding to front pin 32 of cap C, the sides 50 and 51 of the trigger are provided with horizontally elongated slots 53, through which cap pin 32 extends and which have a length equal to the desired amount of movement of the trigger T. Toward the rear, the sides 50 and 51 of the trigger T each become narrower, as at an offset 54 which corresponds in position to slot 28 of the corresponding side 26 or 27 of the cap C as in Fig. 3, while flanges 55 extend inwardly to prevent accidental displacement of spring 36. The rear ends of sides 51 terminate in projections 56, which act as slides, each projection 56 having a depth equal to the distance between the underside of the top 25 of cap C and the central pin 34 thereof, with a slight amount for clearance. As will be evident from Figs. 4 and 8, each projection 56 also fits between the inside of walls 26 or 27 of cap C and the outside of the adjacent block 38, the sides 50 and 51 of the trigger thus limiting lateral movement of the trigger relative to cap C. A pin 57 may extend between the sides 50 and 51 of the trigger T, located to engage catch H in closed position, as well as to provide an abutment for the opposite end of spring 36 and also to add rigidity to the trigger structure, while pin 57 may be a solid pin riveted at its ends to the sides 50 and 51 of the trigger. The trigger may be punched from a strip of brass or other suitable material, such as steel, formed to shape and plated or otherwise treated on the outside to reduce the possibility of rust and corrosion.

The catch H may be a block, substantially rectangular in cross section and formed by casting, or by cutting off individual catches from a strip of cast or extruded material, such as brass or aluminum, which has a cross section similar to that shown in Figs. 2 and 3. The catch H may be provided on the side facing the joint 12 with a latching element, such as a projection or hook 60, preferably having rounded edges, so that the trigger pin 57 will pass thereover smoothly, the hook 60 being disposed above a groove 61 in which the trigger pin 57 engages the latch when the draw bolt is in closed position, as in Fig. 2. Also, the front upper edge 62 of the catch is preferably rounded, so that the roll 33 on cap pin 32 will move thereover easily when the draw bolt is being closed or being opened. The hook 60 and groove 61 preferably extend transversely the full width of the catch, to provide maximum bearing surface for latching, although different configurations thereof may be utilized and different types of latching elements and cooperating latching means on the trigger may be utilized. The upper portions 63 of the sides of the catch may be bevelled,

as in Fig. 5, to insure that the cap and trigger will seat squarely on the catch, since the engagement of rear pin 31 of cap C in slots 43 of base B permit some pivotal movement of the cap in a lateral direction.

5 The assembly of the attaching device of this invention, such as the draw bolt just described, is relatively simple, since the trigger T with the pin 57 attached, may be slipped inside the cap C after the central pin 34 of the cap has been driven into position. The spring 36 may be placed in position as the trigger is inserted in the cap, with the roll 33 of the cap placed between the sides of the trigger, after which the front pin 32 of the cap may be driven into position. The base B and catch H may be attached, as in the manner previously indicated, after which the resilient block R may be placed in the base and the cap fitted thereover, as in the position of Fig. 3, with the holes for rear pin 31 aligned with the base slots 43. Then, the pin 31 may be driven into position and the assembly is complete.

20 The operation of the device of this invention, such as a draw bolt, is very simple, since all that is required to close the draw bolt is to exert pressure on the top of the free end of the cap C, while all that is required to open the draw bolt is merely to exert inward pressure on the front 52 of the trigger T. As will be evident, when the cap C is pushed downwardly from the position of Fig. 3 or Fig. 10, the roll 33 will engage the front rounded edge 62 of the catch H and draw the luggage case sections together. Also, the spring 36 will permit the pin 57 to engage the hook 60 and move the trigger T rearwardly, until the pin 57 can move into groove 61. At the same time, the cap is moved slightly forwardly so that the rear pin 31 will engage and compress resilient block R. Thus, in closed position, any force tending to separate the sections of the luggage case will be resisted by the cap C, through the engagement of roll 33 with catch H and the engagement of pin 31 with block R. Thus, the trigger T is not stressed, since the pin 57 merely prevents the cap from moving upwardly, so that spring 36 need not be as strong as though it were depended upon to hold the draw bolt closed. However, when it is desired to open the draw bolt, rearward pressure on the front 52 of trigger T will compress spring 36, thus permitting the cap C to move upwardly at the front end and the roll 33 to move up over the rounded edge 62 of the catch H. As indicated previously, the resilient block R tends to force cap C upwardly to a sufficient extent that the roll 33 will clear the top of catch H, thus maintaining the cap in an upper position until the case is again to be closed. In addition, the leg 45 of resilient block R tends to prevent accidental displacement thereof.

25 From the foregoing, it will be evident that a device for attaching two separable parts together, such as a draw bolt, for attaching two sections of a luggage case or the like together, fulfills to a marked degree the requirements and objects hereinbefore set forth. The operations necessary for closing the draw bolt are very simple, but the device holds the parts securely together and it does not tend to fly open under heavy stress, since the latching elements which hold the draw bolt closed are not relied on to resist the stress tending to open the case, so that even though a heavy stress is imposed on the device, as by a luggage case which is particularly 30 full of garments or other articles, the operation of the trigger T is not affected. In addition, the resiliency of block R counteracts any slight wear which might take place and also reduces the tolerances necessary for manufacture. As will be evident from the preceding description thereof, the device may be manufactured relatively economically and also may be installed readily. Also, due to the absence of stress on the latching elements, the device is particularly adapted to withstand the rigors of hard usage.

35 70 75 Although a specific embodiment of this invention has

been illustrated and described and variations indicated therein, it will be understood that other embodiments may exist and additional variations may be made, all without departing from the spirit and scope of this invention.

What is claimed is:

1. A device for attaching two separable parts together along a joint therebetween, comprising a base mounted on one said part adjacent said joint; a catch mounted on the other said part adjacent said joint in opposed position to said base; a cap extending across said joint with said parts in closed position; means pivotally mounting said cap on said base; a trigger mounted on said cap for movement relatively thereto, said trigger being provided with means for removably engaging said catch; a block of compressible, resilient material mounted on said base; and means associated with said cap for engaging and compressing said block as said trigger engages said catch.

2. A device for attaching two separable parts together, as defined in claim 1, wherein said means pivotally mounting said cap or said base includes a pivot pin mounted on said cap and a slot in said base in which said pin is movable.

3. A device for attaching two separable parts together along a joint therebetween, comprising a base mounted on one said part adjacent said joint and having laterally disposed flanges and provided with a slot; a catch mounted on the other said part adjacent said joint in opposed position to said base; a cap extending across said joint with said parts in closed position, said cap having a depending flange at each side; a pin extending between said cap flanges and through said base flange slots for pivotally mounting said cap on said base; a trigger mounted on said cap for movement relative thereto, said trigger being provided with means for removably engaging said catch; and a block of compressible, resilient material mounted on said base between said flanges, said cap pin engaging and compressing said block as said trigger engages said catch.

4. A device for attaching two separable parts together along a joint therebetween, comprising a base mounted on one said part adjacent said joint; a catch mounted on the other said part adjacent said joint and in opposed position to said base, said catch having a latching element on the side facing said joint and a rounded upper edge on the opposite side; a cap extending across said joint between said base and said catch with said parts in closed position; means pivotally mounting said cap on said base; a trigger mounted on said cap for movement relative thereto, said trigger being provided with means for removably engaging said latching element of said catch; and means including a roller on said cap for engaging the side of said catch opposite said latching element when said trigger means engages said latching element of said catch.

5. A device for attaching two separable parts together, as defined in claim 4, wherein said latching element of said cap is a hook and said trigger means is a transverse pin engageable with said hook.

6. A device for attaching two separable parts together along a joint therebetween, comprising a base mounted on one said part adjacent said joint; a catch mounted on the other said part adjacent said joint and in opposed position to said base, said catch having a latching element on the side facing said joint; a cap extending across said joint between said base and said catch with said parts in closed position; means pivotally mounting said cap on said base; a trigger mounted on said cap for movement relative thereto, said trigger being provided with means for removably engaging said latching element of said catch; means on said cap for engaging the side of said catch opposite said latching element when said trigger means engages said latching element of said catch; a block of compressible, resilient material mounted on said base; and means associated with said cap for engaging and com-

pressing said block as said catch engaging means of said cap engages said catch.

5 7. A device for attaching two separable parts together, as defined in claim 6, wherein said opposite side of said catch is provided with a rounded upper edge and said catch engaging means of said cap is a rotatably mounted roller.

10 8. A device for attaching two separable parts together, as defined in claim 6, wherein said latching element of said catch is a hook and said trigger means is a transverse pin engageable with said hook.

15 9. A device for attaching two separable parts together along a joint therebetween, comprising a base mounted on one said part adjacent said joint; a catch mounted on the other said part adjacent said joint in opposed position to said base; a cap extending across said joint with said parts in closed position, said cap having a top and depending side flanges; means pivotally mounting said cap on said base; a trigger mounted on said cap between said side flanges for longitudinal movement relative thereto, said trigger being provided with means for removably engaging said catch; a block of compressible, resilient material mounted on said base; and means associated with said cap for engaging and compressing said block as said trigger engages said catch.

20 10. A device for attaching two separable parts together, as defined in claim 9, wherein said cap has an end flange adjacent said base, and the lower end of said end flange is beveled to permit greater upward movement of the opposite end of said cap.

25 11. A device for attaching two separable parts together, as defined in claim 10, wherein said base is provided with upright side flanges and an end flange adjacent said joint, each said side flange having a slot therein; said block is disposed in the space between said side flanges and abuts said base end flange; and a rear pin extends between said cap side flanges and extends through said base flange slots, said rear cap pin being adapted to engage and compress said block upon movement of said cap in one direction.

40 12. A device for attaching two separable parts together, as defined in claim 11, wherein said block is provided with a lower leg extending beneath said rear cap pin.

45 13. A device for attaching two separable parts together, as defined in claim 9, wherein said cap is provided with a central pin and a forward pin, each extending between said cap side flanges; said trigger is provided with sides and a front connecting said sides, each said trigger side having a slot therein through which said front cap pin extends and the rear of each trigger side extends over said center cap pin, said trigger also having a central pin extending between said sides rearwardly of said slots and a flange extending inwardly from each side rearwardly of said trigger pin; and a compression spring is disposed between said cap top and said inwardly extending trigger flanges, one end of said spring engaging said center cap pin and the opposite end of said spring engaging said trigger pin.

55 14. A device for attaching two separable parts together, as defined in claim 9, wherein said catch is generally rectangular in cross section and upstands from said other separable part, the upper front edge of said cap being rounded and the rear side of said cap being provided with a transversely extending groove generally arcuate in section and below a transverse, rearwardly extending projection having rounded upper and lower edges; said trigger is provided with a transversely extending pin for engaging said groove and said trigger is urged forwardly by resilient means acting between said cap and said trigger; and said cap is provided adjacent the front thereof with a roller for engaging the front of said catch and rolling over the rounded upper front edge thereof in moving between disengaging and engaging positions as well as between engaging and disengaging positions.

70 15. A device for attaching two separable parts to-

gether along a joint therebetween, each of said parts having an outwardly extending ledge at said joint, comprising a base mounted on one said part adjacent said joint, said base having a bottom, upright side flanges and an end flange adjacent said joint, with each said side flange having a longitudinally elongated slot therein and the front edge of said bottom abutting said ledge; a catch mounted on the other said part adjacent said joint and in opposed position to said base, said catch abutting at its rear lower edge against said ledge of said other part and said catch being generally rectangular in cross section with the upper front edge thereof being rounded and the rear side thereof being provided with a generally arcuate transversely extending groove disposed below a transversely extending projection having rounded upper and lower rear edges, the upper portion of each side of said cap being beveled inwardly and upwardly; a cap extending across said joint between said base and said catch with said parts in closed position, said cap having a top, depending side flanges, an open front and an end flange disposed rearwardly of said base, the lower end of said end flange and side flange being beveled to permit greater upward movement of the opposite end of said cap, said cap being provided with a rear pin, a central pin and a forward pin, each extending between said cap side flanges with said rear pin extending through said slots in said side flanges of said base and said front pin being provided with a roller for moving over the rounded upper front edge of said catch and engaging said catch on the side opposite said joint, the bottom of each side flange having a groove to fit over said ledges; a trigger mounted in said cap for longitudinal movement relative thereto, said trigger having sides and a front which is concave on the outside and which connects the front ends of said sides, each said trigger side having a longitudinal slot therein through which said front cap pin extends, an offset corresponding in position to said grooves in the bottom of said cap side flanges, an inwardly extending flange rearwardly of said offset and a rearwardly extending projection at the rear end thereof, said trigger also having a pin extending between said sides for engaging said groove of said catch; a coil spring disposed between said cap top and said inwardly extending trigger flanges, one end of said spring

engaging said center cap pin and the opposite end of said spring engaging said trigger pin, said top of said cap having on the underside a pair of laterally spaced, downwardly extending flanges forming a trough therebetween for receiving the top of said spring and connected at the rear end by a downwardly extending abutment engaged by the end of said spring, with a downwardly extending block integral with each said trough flange and disposed outwardly thereof, said projection of each trigger side extending between one of said blocks and the inside of the adjacent side flange of said cap, said projections also being movable longitudinally in the space between said cap top and said cap center pin; and a block of compressible, resilient material disposed in the space between 15 said side flanges of said base and abutting said base end flanges, said block having a lower leg extending rearwardly beneath said rear cap pin and a top beveled upwardly from rear to front, said block having a width less than the distance between said base side flanges to permit compression thereof by said rear cap pin and by the top of said cap.

16. A device for attaching two separable parts together along a joint therebetween, comprising a base mounted on one said part adjacent said joint; a catch mounted on the other said part adjacent said joint in opposed position to said base; a cap extending across said joint with said parts in closed position; means including a pivot pin for pivotally mounting said cap on said base; a trigger mounted on said cap for movement relative thereto, said trigger being provided with means for removably engaging said catch; and a block of compressible, resilient material mounted on said base, said base being connected with said pin so that said pin may move toward and away from said block and will compress said block when said trigger engages said catch.
